GEORGE K. SNOW, OF WATERTOWN, MASSACHUSETTS.

Design No. 4,146, dated June 7, 1870.

DESIGN FOR A COLLAR-BOX.

The Schedule referred to in these Letters Patent and making part of the same.

I, GEORGE K. SNOW, of Watertown, in the State of Massachusetts, have invented and produced a new and original Design, of which the following is a specification.

The object of the design is the production of an attractive box in which to pack paper collars, it having been found that the sales of paper collars depend very much upon the kind of box in which they are packed, those of fanciful and artistic design being most in demand.

The design consists in giving to a paper-collar box

the appearance of a tea-chest. This is done by printing upon the top and sides of the collar-box imitations of the peculiar characters, pictures, and printing ordinarily found upon tea-chests, as is sufficiently illustrated by the photographic drawing.

I claim, as a new and original design, a paper-collar box made to present the appearance of a tea-chest.

GEO. K. SNOW.
